(57) **CLAIM**

The ornamental design for a container lid, as shown and described.

DESCRIPTION

FIG. 1 is a perspective view of an inventive container lid in a closed position with a mated container shown in broken lines;

FIG. 2 is a perspective view of an inventive lid depicted in FIG. 1 in a partially open position;

FIG. 3 is a perspective view of an inventive lid depicted in FIG. 1 in a fully open position;

FIG. 4 is a top view of the inventive lid depicted in FIG. 1; FIG. 5 is a left side view of the inventive lid depicted in FIG. 1;

FIG. 6 is a front view of the inventive lid depicted in FIG. 1;

FIG. 7 is a rear view of the inventive lid depicted in FIG. 1
FIG. 8 is a perspective view of a dimensionally different embodiment of inventive container lid in a closed position with a mated container shown in broken lines;

FIG. 9 is a perspective view of an inventive lid depicted in FIG. 1 in a fully open position;

FIG. 10 is a top view of the inventive lid depicted in FIG. 1;

FIG. 11 is a left side view of the inventive lid depicted in FIG. 1;

FIG. 12 is a front view of the inventive lid depicted in FIG. 1; and,

FIG. 13 is a rear view of the inventive lid depicted in FIG. 1.

The broken lines in the drawings are for illustrative purposes only and form no part of the claimed design.
